United States Patent Office

Des. 218,848
Patented Sept. 29, 1970

218,848

HOLDER FOR GARBAGE CANS

Lewis J. Woods, 2328 W. Vliet St.,
Milwaukee, Wis. 53205

Filed June 30, 1969, Ser. No. 17,979

Term of patent 14 years

Int. Cl. D7—99

U.S. Cl. D49—33

FIG. 1 is a front perspective view of a holder for garbage cans showing my new design; and

FIG. 2 is an end perspective view of the unit.

I claim:

The ornamental design for a holder for garbage cans, as shown.
